UNITED STATES PATENT OFFICE.

EDWARD J. WEEKS, OF NEW YORK, N. Y., ASSIGNOR OF FORTY ONE-HUNDREDTHS TO J. VEIT, OF NEW YORK, N. Y.

ROTARY ENGINE.

No. 830,123.

Specification of Letters Patent.

Patented Sept. 4, 1906

Application filed February 2, 1906. Serial No. 299,221.

To all whom it may concern:

Be it known that I, EDWARD J. WEEKS, a citizen of the United States, residing at New York, in the county of New York and State 5 of New York, have invented certain new and useful Improvements in Rotary Engines, of which the following is a specification.

In motors of the rotary type as heretofore constructed difficulty is experienced in maintaining a tight joint between the operating parts and in preventing the consequent waste of power and the backlash due to leakage of the motive medium. Moreover, the developed power available for effective 15 work does not represent the units of force expended for operating the engine by a very material margin.

This invention provides an engine of exceedingly simple construction, light, compact, durable, and capable of converting a maximum percentage of the power into working force.

The engine comprises, essentially, three parts—a hub, a cylinder, and a pair of piston-rings, the latter having pistons or abutments extended inward into the space formed between the rings therefrom in alternation and dogs or clutch elements coöperating with the piston-rings for securing them to the hub and cylinder, respectively, in successive order, whereby the piston-rings receive a step-by-step movement which is imparted to the driven part, whether the hub or cylinder.

The invention consists of the novel features and details of construction which hereinafter will be more particularly set forth, illustrated, and finally claimed.

In the drawings hereto attached and forming a part of the specification, Figure 1 is a 40 perspective view of a rotary engine embodying the invention, a portion of the cylinder or casing being broken away and the mountings and pipe connections being omitted. Fig. 2 is a central longitudinal section of the 45 engine on a larger scale. Fig. 3 is a section on the line 3 3 of Fig. 2, showing one of the piston-rings in locked engagement with the cylinder or casing and the other piston-ring about to make locked engagement with the 50 hub. Fig. 4 is a section on the line 4 4 of Fig. 3, showing the piston-rings having a different relative arrangement. Figs. 5 and

6 are sectional views similar to Figs. 3 and 4, showing different positions of the piston-rings. Fig. 7 is a detail perspective view of 55 the hub. Fig. 8 is a detail perspective view of the cylinder or casing. Fig. 9 is a detail perspective view of a piston-ring, showing the clutch elements disconnected therefrom and arranged opposite their respective seats 60 or openings in the pistons or abutments. Fig. 10 is a front view of the engine, on a smaller scale, illustrating the mountings therefor and the inlet and outlet for the motive medium. Fig. 11 is an enlarged view 65 showing the clutch engaged with the cylinder. Fig. 12 is a detail view of a modification, showing independent clutch elements between the piston-ring and the hub and cylinder. Fig. 13 is a cross-section on the 70 line z z of Fig. 12.

Corresponding and like parts are referred to in the following description and indicated in all the views of the drawings by the same reference characters.

The hub 1 receives the piston-rings 2 and 3, which are spaced apart and provided with pistons or abutments 4 and 5, respectively, of a length to extend across the space formed between the two rings and of a width depending upon the size of the engine to leave a space between the piston corresponding to the predetermined step-by-step movement thereof. The number of pistons or abutments may vary according to the capacity 85 and size of the engine, each piston-ring being provided with a like number of abutments. The piston-rings are provided with dogs or clutch elements 6, constructed to alternately interlock with the cylinder and hub in the 90 operation of the engine. The clutch may be conveniently arranged so as to obtain the best results, and in order to admit of the piston-rings being of a minimum thickness it has been found advantageous and economical 95 to apply the clutch elements 6 to the abutments or pistons by snugly fitting them in openings or seats 7 thereof for free radial movement. This construction provides a clutch dog or element for each piston or abutment and makes provision for a maximum amount of gripping-surface between the said dogs and the hub or cylinder. The dogs or clutch elements 6 are longer than the radial 100

distance between the inner and outer surfaces of the pistons or abutments, so as to project beyond the same and make interlocking engagement with either the hub or 5 the cylinder, as shown most clearly in the several cross-sectional views.

The cylinder or casing 8 snugly encircles the piston-rings and pistons and is provided upon its inner side with a series of grooves or 10 seats 9 to receive the outer ends of the dogs or clutch elements 6 when in interlocking engagement therewith. The ends of the cylinder are closed by heads 10, forming a part of or connected to the hub 1. Obviously the 15 said heads may be connected to or formed with the cylinder and made loose with reference to the hub so long as provision is had for independent movement of the hub and cylinder, while at the same time maintaining 20 a steam-tight closure at the ends of the cylinder and between said ends and the corresponding portions of the hub.

The hub 1 is hollow and provided with a plurality of passages or ducts 11 and 12, the 25 latter constituting inlets for the motive medium and the former providing outlets for said medium after it has spent its force in driving the engine. Ports 13 are provided in the sides of the hub and communicate 30 with the inlet passages or ducts 12, and other ports 14 are similarly formed in the sides of the hub and are in communication with the exhaust-passages 11. The inlet-ports are considerably smaller than the exhaust-ports 35 and are disposed so as to direct the motive medium between the two sets of pistons or abutments when moving forward at the initial stroke. By having the exhaust-ports 14 comparatively large a free escape is provided 40 for the spent medium, thereby minimizing the resistance from this source. The inlet-passages 12 are closed at one end and are open at the opposite end to communicate with the pipe 15, by means of which the motive medium is supplied to the engine. The 45 exhaust-passages 11 are closed at one end and are open at the opposite end and in communication with the pipe 16 by means of which the exhaust is conveyed to the suitable 50 point of discharge.

In the construction of the engine there is a definite relation between the pistons, inlet, and exhaust-ports, and the clutch mechanism between the pistons, hub, and cylinder 55 to insure an alternate movement of the piston-rings and attached pistons and the opening and closing of the ports in alternation, whereby the piston-rings receive a step-by-step movement in successive order, the pistons of one ring forming relatively fixed 60 abutments, while the pistons of the other ring are driven forward, and so on in alternation.

So far as the scope of the invention is con-

cerned it is immaterial which of the parts is 65 stationary and which movable. In the drawings the hub is stationary and is mounted in bearings 17, whereas the cylinder 8 is rotatable and the power is taken therefrom for driving the machinery to be operated. 70 Obviously by making the cylinder stationary the hub becomes the movable part and the power may be taken therefrom in any approved manner for driving any mechanism to be mechanically operated. 75

The motive medium may be steam, compressed air, water, or other agent commonly employed for operating engines. A single pair of piston-rings and adjunctive parts may comprise a working engine, in which case the 80 momentum of a fly-wheel or other part of the engine is utilized to carry one of the piston-rings forward from the point of exhaust to the point for receiving the motive agent. The best results are obtained by having the engine 85 comprise a number of pairs of piston rings. As illustrated, the engine comprises two pairs or sets of piston-rings. Within the purview of the invention the engine may comprise any number or pairs of piston-rings 90 arranged in successive operation, thereby obviating the formation of a dead-center and enabling the engine to be started from any point of rest without the intervention of extraneous means. In the preferable type of 95 engine the hub is stationary and the cylinder rotatable and two or more pairs of piston-rings and adjunctive parts are provided and disposed to overlap or operate in succession.

As shown in Fig. 3, the cylinder 8 occupies 100 a position with reference to the hub and the piston-ring 2, showing the dogs or clutch elements 6 in the act of releasing the pistons 4 from the cylinder and about to enter the seats or grooves 18 of the hub so as to interlock therewith and hold the pistons 4 stationary while the pistons 5 are driven forward a distance corresponding to the predetermined stroke of the pistons. When the pistons 4 become clutched or locked to the 105 hub, they form fixed abutments, and the pistons 5 are driven forward by the motive medium passing between the pistons 4 and 5 from the inlet-passages through the ports 13. Fig. 4 shows the position of the parts when 110 the piston-ring 3 has moved forward a distance to bring the pistons 5 in contact with the pistons 4. Fig. 5 shows the pistons in such a position as to uncover the inlet and 115 exhaust ports, and Fig. 6 shows said ports uncovered by the pistons during which period one set of pistons must be carried forward either by the momentum of the engine or by the pistons of the set positively driven 120 when the engine comprises a number of pairs 125 of pistons. The seats or grooves 9 are bevelled upon their rear walls, and the outer rear corners of the dogs or clutch elements 6 are

correspondingly beveled. The front walls of the grooves or seats 18 are forwardly beveled, and the inner front corners of the parts 6 are correspondingly beveled. Hence said 5 dogs or clutch elements are positively moved inward and outward by a wedging action due to the beveled, inclined, or cam portions riding upon each other, as will be readily comprehended. When the outer ends of the 10 dogs are seated in the grooves 9, the inner ends are riding upon the portion of the hub between the grooves or seats 18, and as said inner ends register with the grooves 18 they are forced therein by the riding of the outer 15 beveled or cam ends of the dogs upon the beveled or cam sides of the seats 9. When the pistons previously at rest are driven forward, the inner ends of the dogs 6 are forced from the grooves or seats 18 into the 20 grooves or seats 9, and the pistons previously driven forward become stationary for the instant to receive the back pressure of the motive medium while the pistons just released are urged forward. The engine is driven by 25 a succession of impulses due to the step-by-step movement of the piston, as herein described.

In the construction shown in Figs. 12 and 30 13 the clutch elements are applied to the piston-ring and are of such formation as to grip the hub and cylinder in the well-known manner to effect the results herein stated. The clutch elements, as shown, consist of 35 rollers 6^a, fitted into seats 19, which have one face square and the other inclined to reduce the space and compel the elements 6^a to grip either the hub or cylinder by a wedging action in the well-known manner. When the piston-ring moves forward the outer clutch 40 elements 6^a engage with the cylinder and carry the same forward; but when the pistons of one ring impact against the pistons of the other or companion piston-rings the advancing or driving piston-ring is arrested and it 45 becomes disengaged from the cylinder and clutches or grips the hub so as to hold the pistons stationary while forming fixed abutments to receive the back pressure of the motive medium as the pistons previously stationary are advanced. It is to be understood that two piston-rings are provided and that each is similarly equipped, the operation being substantially the same as that 50 herein described, the only difference being in the formation and adaptation of the clutch 55 elements.

The piston-rings 2 and 3 are of a size to snugly fit the space between the hub and cylinder, so as to divide said space for the separate 60 sets of pistons and to close the ends thereof, as shown most clearly in Figs. 1 and 2. The pistons project laterally from the respective rings and are in the plane thereof, the inner and outer surfaces coming flush

with the respective inner and outer edges 65 thereof.

Having thus described the invention, what is claimed as new is—

1. An engine of the rotary type comprising a hub and cylinder concentrically arranged, 70 pistons located in the space formed between the hub and cylinder and adapted to be driven in alternation, means for admitting and exhausting the motive agent, clutch elements for alternately connecting the pistons 75 to the hub and cylinder, means for positively disconnecting the clutch elements from either the hub or cylinder and at the same time causing them to engage with the opposite part, and rings for the respective pistons 80 closing the space formed between the hub and cylinder, substantially as set forth.

2. An engine of the rotary type comprising a hub and cylinder concentrically arranged, sets of pistons located in the space formed 85 between the hub and cylinder, the pistons of each set being adapted to be driven in alternation, means for admitting and exhausting the motive agent, clutch elements movable with reference to the pistons and of a 90 length to project beyond the same so as to engage with either the cylinder or hub to make interlocking connection therewith, and rings carrying the pistons of the respective 95 sets and adapted to divide the space formed between the hub and cylinder and to close said space at its ends, substantially as set forth.

3. In combination, a cylinder, a hollow hub concentric therewith and subdivided into a plurality of passages which are closed 100 at opposite ends in alternation to form inlets and outlets, which communicate with the space formed between the hub and cylinder by means of openings in the walls or sides of the hub, pistons arranged to travel in the 105 space formed between the hub and cylinder, and clutch elements applied to the pistons for alternately connecting them to the hub and cylinder, substantially as specified.

4. A rotary engine comprising a cylinder, 110 a hollow hub concentric therewith and subdivided longitudinally into a plurality of passages which are closed at opposite ends in alternation and form inlets and outlets having communication with the space formed 115 between the hub and cylinder by means of openings formed in the sides or walls of the hub, a head closing one end of the cylinder and formed with the hub, a head closing the opposite end of the cylinder and threaded 120 upon the hub, rings arranged within the space formed between the hub and cylinder and subdividing the same and touching the walls of said parts at their respective opposite edges, pistons projected laterally from corresponding rings, the pistons of one set of rings being alternately disposed with reference to 125 the pistons of the corresponding set of rings,

clutch elements applied to the pistons for connecting them in alternation to, respectively, the hub and cylinder, and means for supplying the motive medium to one end of the hub and carrying off the medium from the opposite end of the hub after it has spent its force, substantially as set forth.

In testimony whereof I affix my signature in presence of two witnesses.

EDWARD J. WEEKS. [L. S.]
